D23-346

EX

D7463

OR D 13,172

No. 13,172

Aug. 15, 1882

UNITED STATES PATENT OFFICE.

EDGAR W. ANTHONY, OF BOSTON, MASSACHUSETTS, AND THOMAS J. GOULD, OF PROVIDENCE, RHODE ISLAND, ASSIGNEES TO THE SMITH & ANTHONY STOVE COMPANY, OF BOSTON, MASSACHUSETTS.

DESIGN FOR A HEATING-STOVE.

SPECIFICATION forming part of Design No. 13,172, dated August 15, 1882.

Application filed May 19, 1882. Term of patent 14 years.

To all whom it may concern:

Be it known that we, EDGAR W. ANTHONY, of Boston, in the county of Suffolk and State of Massachusetts, and THOMAS J. GOULD, of Providence, in the county of Providence, in the State of Rhode Island, both citizens of the United States, have invented and produced a certain new and original Design for Heating-Stoves, of which the following is a full, clear, and exact description, reference being had to the accompanying photograph, making a part of this specification, in explaining its details.

The leading feature of the stove is the base portion, which is very nearly square, being of a somewhat greater dimension across the front than across the end, and contains the ash-pit chamber and fire-pot, and the upper section, which is somewhat smaller in dimensions than the lower or base section, is concentrically arranged over it, and contains the combustion-chamber, and, if desired, a magazine. The height of the base-section preferably is somewhat greater than the height of the upper section. These two sections are suitably ornamented upon the ends and front, as hereinafter specified.

Referring to the photograph, A is the base-section, and B the upper section. a represents the front of the stove, and b one end or side.

Upon the front of the base-section there are the ash-pit door a', which preferably is ornamented by cross-bars and curved openings, or openings having curved sides, as shown in the photograph, and the upper or fire-pot door, a'', which has preferably an open-work door for the reception of mica or other transparent lights, and which has a series of cross-bars and the other ornamentation shown by the photograph.

Below the ash-pit door is the rounded section a³, having open-work figures in straight and circular lines, substantially as represented by the photograph. Between the two doors is the plate or panel a⁴, which also has one of the features of the general ornamentation of the stove—namely, the straight bars and the circular figures. Reference is made to the photograph for a further description of this plate or panel.

Upon each side of the circular section of the front, which comprises the ash-pit and fire-pot doors and the intermediate panel, is the intermediate open-work section, a⁵, which extends from the section a³ to the plate a⁶, and which are well represented by the photograph. Immediately adjacent to these sections a⁵ are the corner sections or plates a⁷, and they consist of an arrangement of cross-bars, ribs, or ridges forming small cells or recesses, which are very well represented in the photograph. These sections or plates have also an additional horizontal bead-work, as represented.

The side or end corner plate or section, b', two of which are shown in the photograph, are like the corner sections, a⁷, with the exception that, if preferred, two or more representations, b², of a circular character—sunflowers or the like, if desired—are formed thereon. Within these corner plates or sections are two long panels, b³, and between these panels is the large ornamental panel b⁴, which is very nearly square, being a little higher than it is wide.

Dividing the sections a⁵ from the front section and from the corner section and the long panels b³ from the central panel and the side sections, b', are the vertical raised ribs or relief bars or borders c, which extend from the section a³ to the plate a⁶, and near the top there is a horizontal raised relief rib or bar, c'. Above this horizontal raised rib c', upon the front and upon either side of the fire-pot door a⁵ and extending the whole width of the side, is the ornamental section c². The lower plate, d, of the stove preferably projects somewhat more at the front than at the sides, and may have a burnished or polished edge. Between its upper surface and the section a³ there may be molded work of a more or less ornamental nature.

Below the plate d is the stand or base d' of the stove, which is ornamented upon the front d² and side d³, as shown, and which has legs d⁴, which are also of the general configuration and bear the ornamentation represented by the photograph.

The central plate, a⁶, separates the base-section A from the upper section, B, and it projects somewhat beyond the sides of the base

95

(Over)

portion, as represented. Its edge may be polished or burnished. Rising from this plate is the upper section, B, and it is divided substantially into four sections. The first section, 5 e , is that portion of the stove between the doors e' and the plate a^6 , and the general shape and ornamentation of this section are well shown by the photograph. There are half-rosettes e^2 thereon, which are arranged to be on a line 10 with the raised relief ribs or borders e of the base. The doors e' comprise the second section, and they have mica or other transparent lights and are ornamented as shown by the photograph. Above the doors is the third 15 section, e^3 , in which are arranged tiles e^4 , or panels of an ornamental character; and above this section is the fourth section, e^5 , which comprises the top plate of the stove and the door to the magazine. The top plate, e^5 , projects 20 beyond the vertical sides of the upper section, as shown, and there is suitable relief-molding between its under surface and the section e^4 . The edge of this plate is burnished, if preferred, and its upper surface is suitably ornamented with scroll-work about midway between the edge and the cover e^7 to the magazine. This cover e^7 is a flat plate with a more or less ornamented or molded edge, e^8 , and having suitable ornamentation upon its upper surface, if desired, and from which rise the supports e^9 for the rails e^{10} .

Between the section e^3 and the section e^4 there is relief-molding of a suitable character, and the corners of the upper section between 35 the doors are ornamented by means of the horizontal lines, as represented.

The hinges of the various doors are of the same general character—that is, they are round with parallel lines arranged in sections 40 tending about them and about the supports for the same, as shown.

Upon the section e of the stove is arranged at either side or end brackets f for supporting the rail f' , and upon the front of the base-section there are brackets f^2 , which support the rail f^3 . These rails $f' f^3$ are preferably of brass, copper, or of burnished iron, or are nickel-plated.

Of course the doors may have in lieu of the 50 mica or other lights a plain metal plate upon which the ornamental work shown shall be raised.

It will be observed that, aside from the feature that is provided the design on account of 55 the proportions and arrangements of the two sections A, B in relation to each other, the principal elements of the design are in the section B, the line or upper section of ornamental panel-work, either tiles or metal, and 60 the lower section or frame-work for the reception of the mica lights; and that of the base portion A the elements which stand out as characteristic of the design are the two doors, the large central panel, b^4 , the corner sections, 65 and the raised border or ribs.

Having thus fully described my improved design and its features, I claim and desire to

secure by Letters Patent of the United States—

1. The design for a stove-leg, substantially as shown and described. 70

2. The design d' for a base or support, substantially as shown and described.

3. The design a^2 for a stove-panel door or frame for lights, substantially as shown and described. 75

4. The design a' for a stove-door, substantially as shown and described.

5. The design e' for a stove door or panel, substantially as shown and described.

6. The design a^1 for a stove-panel, substantially as shown and described. 80

7. The open-work design a^5 , substantially as shown and described.

8. The corner sections, a^7 , substantially as shown and described. 85

9. The long ornamental panels b^3 , substantially as shown and described.

10. The panel b^4 , substantially as shown and described.

11. The section e^2 , substantially as shown 90 and described.

12. The open-work section a^3 , substantially as shown and described.

13. The section e , substantially as shown and described. 95

14. The section e^5 , substantially as shown and described.

15. The upper plate, e^5 , substantially as shown and described.

16. The cover e^7 , standards e^9 , and rails e^{10} , substantially as shown and described. 100

17. The ornamental hinges, substantially as shown and described.

18. The ornamental brackets f^2 and rail f^3 , substantially as shown and described. 105

19. The raised border e^9 , substantially as shown and described.

20. The base-section A of a stove, having the upper door, a^2 , and the lower ash-pit door, a' , and an intermediate ornamental panel and ornamentation upon each side thereof, substantially of the character indicated, all as shown and described. 110

21. The base A, having a large central panel, b^4 , surrounding ornamental panels and borders and corners of the nature indicated, all substantially as shown and described. 115

22. The design for the upper section, B, of a stove, comprising the sections $e e' e^3 e^5$, all substantially as shown and described. 120

23. The design for a stove, rectangular in cross-section, having the base and upper sections, A, B, shaped and proportioned in outline and size as shown and described.

24. A design for a heating-stove, rectangular in cross-section, having the base and upper sections, A, B, shaped and proportioned to each other substantially as shown and described, the upper of which sections has a line of tile or panel-work and ornamental frame-work for the reception of mica lights, and the lower of which sections has two ornamental doors upon the front and a large central panel upon the side, all substantially as shown and described. 125

25. The design for a heating-stove, rectangular in cross-section, having the base-plate d , the base-section A with front and side ornamentation, substantially as shown and described, the plate a^6 , and the upper section, B, ornamented, 5 as shown and described.

26. The design for a heating-stove, comprising the vertical border or raised portions or lines c and the horizontal border or raised

portion c' , arranged to divide the surface of 10 the stove into panels, all substantially as shown and described.

EDGAR W. ANTHONY.
